UNITED STATES PATENT OFFICE.

GEORGE H. CORMACK, OF ROCKFORD, ILLINOIS.

CAR-SIGNAL.

SPECIFICATION forming part of Letters Patent No. 290,540, dated December 18, 1883.

Application filed June 4, 1883. (No model.)

To all whom it may concern:

Be it known that I, GEORGE H. CORMACK, a citizen of the United States, residing in the city of Rockford, in the county of Winnebago 5 and State of Illinois, have invented a new and useful Signal for Railroad-Cars, of which the following is a specification.

This invention relates to signal-lights employed on cars in moving railroad-trains; and 10 its object is to provide a signal-light for moving trains of a character to determine whether or not the train of cars is in motion, and by which to approximately determine the velocity of the moving train; and it consists in a movable cut-off operated by the movement of the train, to vibrate or pass in front or rear of the light, or both in front and rear thereof. I attain these objects by the mechanism illustrated 15 in the accompanying drawings, in which—

Figure 1 is an end elevation of a car with my improved signal in place thereon. Fig. 2 is a side elevation of an end portion of a car, showing my improvements in place thereon; and Fig. 3 is an isometrical representation of a cut-off designed to operate on both sides of the signal-light.

In the figures, A represents the end, and B a portion of the side, of a car-body mounted upon a suitable truck-frame, C, supported on 30 truck-wheels D, fixed on the axle-tree E to revolve therewith, all of which are substantially the same as cars now in general use on railroads.

At a is represented a signal-light, such as is in common use on cars, and is supported on a 35 bracket, b, fixed to the car, a convenient position being on the side of the car near the end thereof.

At c is represented a cut-off lever, having its fulcrum-support at d, on the same horizontal 40 plane with the signal-light, in such position thereon that its free end will extend past the light, and of such width as to fully cover the light when over its center. The inner end of this cut-off lever has a pivotal joint connection 45 at e with a connecting rod or link, h. The lower end of the connecting-rod h is pivot-jointed to the forward end of the horizontal arm i of the bell-crank lever k, which is provided at its angle-point with a fulcrum-support, m, on 50 which it oscillates. The vertical or depending

arm n of this bell-crank lever is produced in yoke form, as at o, to embrace an eccentric, p, fixed upon the axle-tree E of the wheeled truck. This eccentric in this instance is produced in two parts, provided with radial flanges p, to receive clamping screw-bolts, to fix it in place on the axle-tree. From the foregoing it will be seen that when the train or car is in motion the bell-crank, by means of its connection with the eccentric on the axle-tree of the truck, will 55 be made to oscillate on its fulcrum-support, as indicated by the dotted lines, which motion will be transmitted through the connections, causing the pivoted lever cut-off to vibrate in front of the light twice in each revolution of the 60 truck axle-tree.

At the left-hand side of Fig. 1, I have represented the cut-off lever H, having its fulcrum-support I on a horizontal plane at or about the upper side of the signal-light in such position 70 that in its vibrations the cut-off shall descend to cover the light, as shown in the dotted lines, and in its upward movements shall rise above the light to the position in the solid lines. In this application of the cut-off it will be seen that 75 the cut-off shades the light but once in each revolution of the truck axle-tree, and consequently the alternate intervals of light and shade are less frequent and of greater duration than in the preceding example hereinbefore described, and shown on the right-hand side of the figure.

At Fig. 3 I have represented a form of cut-off lever provided with a double cut-off blade, N and P, suitably separated to receive the signal-light between them, and in its vibrations to pass on both sides of the light, which will render it an efficient front and rear cut-off. From the foregoing it will be seen that when the train or car is at rest, this cut-off will also be 80 at rest, and when the train is in motion it will impart motion to the cut-off, and the velocity of the vibrations of the cut-off will indicate the velocity at which the train is moving.

In the dotted lines R is represented a bar-lever having a pivotal connection with the truck-frame, from which point it extends forward, having its yoke portion embrace the eccentric, and its forward end connects with the depending end portion, s, of the connecting- 95 100

rod shown in dotted lines. In some instances this form of lever may be preferred to the bell-crank lever hereinbefore described.

I am aware that it is not broadly new to provide a signal-light with a cut-off lever operated by the movement of the train, to intermittently intercept the rays of light; hence I make no broad claim to such a device; but

I claim as my invention—

10 1. The combination, with an eccentric mounted upon the axle-tree of the wheeled truck, and with a pivoted lever cut-off, of a pivoted lever having a yoke-connection with the eccentric, and a rod or link connecting the yoke-

lever with the lever cut-off, substantially as 15 and for the purpose set forth.

2. The combination, with a signal-light, of a pivoted cut-off lever to intermittently intercept the rays of light, an eccentric mounted upon the axle of the wheeled truck, and mechanism 20 operated by said eccentric to automatically vibrate said pivoted cut-off lever, substantially as set forth.

GEORGE H. CORMACK.
